(57) **CLAIM**

The ornamental design for a cutting insert, as shown and described.

DESCRIPTION

FIG. 1 is a front perspective view of a cutting insert showing my new design;

FIG. 2 is a front view thereof;

FIG. 3 is a top view thereof;

FIG. 4 is a left side view thereof;

FIG. 5 is a rear view thereof;

FIG. 6 is a bottom view thereof;

FIG. 7 is a sectional view thereof taken along line 7-7 in FIG. 3;

FIG. 8 is an enlarged partial top view thereof;

FIG. 9 is a top view thereof; and,

FIG. 10 is a sectional view thereof taken along line 10-10 in FIG. 9.

The broken lines in the drawings depict unclaimed environmental subject matter. The dash-dot-dash lines directly adjacent to the claimed areas are included to represent the boundaries of the claimed design and form no part of the claimed design.
